UNITED STATES PATENT OFFICE

130,762

DESIGN FOR A CIRCUMCISION RING

Cecil J. Ross, Portland, Oreg.

Application February 1, 1941, Serial No. 98,655

Term of patent 3½ years

To all whom it may concern:

Be it known that I, Cecil J. Ross, a citizen of the United States, residing at Portland, in the county of Multnomah and State of Oregon, have invented a new, original, and ornamental Design for Circumcision Rings, of which the following is a specification, reference being had to the accompanying drawing, forming a part thereof.

Figure 1 is a rear view of a circumcision ring showing my new design;

Figure 2 is a side elevational view, and Figure 3 is a front view of the circumcision ring shown in Figure 1.

I claim:

The ornamental design for a circumcision ring, as shown.

CECIL J. ROSS.
